UNITED STATES PATENT OFFICE.

JEAN BAPTISTE DAUDELIN, OF FALL RIVER, MASSACHUSETTS, ASSIGNOR
TO JOHN SHAMBOW AND CHRISTOPHER J. SHAMBOW, OF WOONSOCKET,
RHODE ISLAND.

SELF-THREADING LOOM-SHUTTLE.

No. 849,212.

Specification of Letters Patent.

Patented April 2, 1907.

Application filed April 21, 1904. Serial No. 204,212.

To all whom it may concern:

Be it known that I, JEAN BAPTISTE DAUDELIN, a citizen of the United States, residing at Fall River, in the county of Bristol and Commonwealth of Massachusetts, have invented certain new and useful Improvements in Self-Threading Loom-Shuttles, of which the following is a specification:

This invention relates to self-threading shuttles, and particularly to that class in which the thread when in the delivery-eye is deflected or held away from the passage by which it entered by a bar, shoulder, or projection of some sort. It is particularly desirable in these shuttles to have an eye which will be capable of easy and accurate adjustment and which will be held firmly in place in the shuttle-body.

To this end the present invention contemplates the use of a delivery-eye or bushing which shall have such a construction and arrangement of parts as will make possible such an adjustment and ease and accuracy in the disposition of the slots in the shuttle-body and bushing, through which the thread must pass to enter the eye.

In the drawings, in which like letters of reference indicate corresponding parts throughout, Figure 1 is a view of one end of such a shuttle. Fig. 2 is a section on the line 2-2 Fig. 1. Fig. 3 is a view of the delivery-eye, and Fig. 4 a modification of the same.

There is shown a shuttle of the type above mentioned, the actual shuttle shown being that of my Patent 7,56,592.

In the shuttle-body A is a delivery-eye D, in which is located a bushing or delivery-eye E. This eye consists of a tubular body portion B, closed at one end and having a threaded and slotted head H, the slot h being adapted to receive a screw-driver for driving the eye in the shuttle-body and adjusting the same after it is located therein. The body portion B may be also screw-threaded to engage the wood of the shuttle-body and act as a transverse strengthening-bolt.

E' is an opening through which the thread

is drawn into the tubular body B, and E² is a slot connected therewith to allow the thread, which passes through the threading-passage F in the shuttle-body, to enter the eye. The portion of the eye E adjacent to this slot is cut down or cleared, as at S, to allow the thread to pass between the eye and the shuttle-body. This cleared portion S may be in the form of a sunken or recessed area, as shown in Fig. 3, or the body B may be gradually thinned or tapered at this edge to allow the thread to enter the slot, as shown in Fig. 4.

In assembling the parts the eye is introduced into the shuttle-body and screwed in, it being turned until the slot E² registers with the passage F in the shuttle-body. If at any time the eye becomes displaced or the edges of the passages wear down, the parts may be immediately adjusted by simply turning the bushing with a screw-driver in the slot h.

What I therefore claim, and desire to secure by Letters Patent, is—

1. A bushing for a self-threading shuttle having a threaded portion, a threading-slot throughout a part of its length, and a cleared portion adjacent to said slot and on one side thereof.

2. In a self-threading shuttle, the shuttle-body having a threading-passage and delivery-eye, a bushing having a threaded portion, a threading-slot and a cleared portion on one side of and adjacent to said slot and connecting with the threading-passage of the shuttle.

3. A bushing for a self-threading shuttle having a threading-slot and a cleared portion at the edge of said slot.

4. In a self-threading shuttle, the shuttle-body having a delivery-eye and threading-passage, a bushing for the delivery-eye, said bushing having a threading-slot therein and a cleared portion on the edge of the slot and connecting with the threading-passages of the shuttle.

5. A bushing for a self-threading shuttle, having an unthreaded portion of reduced

diameter between its end portions, one of the latter being externally threaded, and a slot extending from one end of the bushing and terminating in said portion of reduced diameter.

5. A bushing for a self-threading shuttle, having a solid, externally-threaded head slotted at its end, a tubular body portion having a longitudinal threading-slot throughout

a part of its length, and a cleared portion adjacent and on one side of the threading-slot.

In testimony whereof I affix my signature in presence of two witnesses.

JEAN BAPTISTE DAUDELIN.
